UNITED STATES PATENT OFFICE

DANIEL S. BEARS, OF EDGEWOOD, RHODE ISLAND, ASSIGNOR TO RELIANCE MANUFACTURING COMPANY, A CORPORATION OF RHODE ISLAND

DESIGN FOR A LINK UNIT FOR A CHAIN, BRACELET, PENDANT OR THE LIKE

Application filed October 10, 1931. Serial No. 41,361. Term of patent 3½ years.

To all whom it may concern:

Be it known that I, DANIEL S. BEARS, a citizen of the United States of America, residing in Edgewood, county of Providence, State of Rhode Island, have invented a new, original, and ornamental Design for a Link Unit for a Chain, Bracelet, Pendant or the like, of which the following is a specification, reference being had to the accompanying drawings, forming a part thereof.

Fig. 1 is a top plan view; Fig. 2 is a side elevation; and Fig. 3 is a section on line 3—3 of Fig. 1 of a link unit for a chain, bracelet, pendant or the like, showing my new design.

I claim:

The ornamental design for a link unit for a chain, bracelet, pendant or the like, substantially as shown.

DANIEL S. BEARS.
